UNITED STATES PATENT OFFICE.

ADOLPH MONTFORT, OF CHICAGO, ILLINOIS.

DESIGN FOR A STRINGED MUSICAL INSTRUMENT.

Application filed June 14, 1926. Serial No. 18,046. Term of patent 7 years.

To all whom it may concern:

Be it known that I, ADOLPH MONTFORT, a citizen of the United States, residing at Chicago, in the county of Cook and State of Illinois, have invented a new, original, and ornamental Design for a Stringed Musical Instrument, of which the following is a specification, reference being had to the accompanying drawing, forming a part thereof.

I claim:

The ornamental design for a stringed musical instrument as shown.

ADOLPH MONTFORT.
